UNITED STATES PATENT OFFICE.

ARTHUR W. BARNARD, OF NEWTON, AND JOHN W. McMILLAN, OF MARSHFIELD,
MASSACHUSETTS, ASSIGNEES TO COLONIAL SCALE COMPANY, A CORPORATION
OF MASSACHUSETTS.

DESIGN FOR A WEIGHING-SCALE.

50,804.

Specification for Design.

Patented May 22, 1917.

Application filed February 28, 1917. Serial No. 151,570. Term of patent 7 years.

To all whom it may concern:

Be it known that we, ARTHUR W. BARNARD, a citizen of the United States, residing at Newton, in the county of Middlesex and State of Massachusetts, and JOHN W. McMILLAN, a citizen of the United States, residing at Marshfield, in the county of Plymouth and State of Massachusetts, have invented a new, original, and ornamental Design for a Weighing-Scale, of which the following is a specification, reference being

had to the accompanying drawing, forming part hereof, in which—

Figure 1 is a perspective view of a weighing scale embodying our invention;
Fig. 2 is an elevation of the same; and
Fig. 3 is a plan of the same.

We claim:

The ornamental design for a weighing scale as shown.

ARTHUR W. BARNARD.
JOHN W. McMILLAN.
